UNITED STATES PATENT OFFICE.

WILLIAM M. MORSE AND MORRIS G. KNOX, OF HARMAR, OHIO.

IMPROVEMENT IN HEATING-STOVES.

Specification forming part of Letters Patent No. 171,691, dated January 4, 1876; application filed December 11, 1875.

To all whom it may concern:

Be it known that we, WILLIAM M. MORSE and MORRIS G. KNOX, of Harmar, Washington county, Ohio, have invented a new and Improved Heating-Stove, of which the following is a specification:

Our invention consists in the upper portion of the cylinder stove constructed in one or more sections, formed with large radial inlet air-pipes and a central vertical pipe, which connects with a discharge-passage in the top plate for the air, thus making a contrivance whereby a lively circulation of air is maintained through the upper portion of the air-chamber, and thus the heat of the fire is utilized to a greater extent.

Figure 1 is a sectional elevation of our improved stove; and Fig. 2 is a horizontal section taken on the line $\alpha\alpha$, Fig. 1.

Similar letters of reference indicate corresponding parts.

A and B represent a couple of sections of the upper portion of the stove-cylinder C, each having, say, four radial tubes, D, leading from the extension of the cylinder to the center, where they connect with a vertical

passage, E, connecting with a passage, F, through the top of the stove, so as to cause the air to enter from the sides and pass through the upper portion of the fire-chamber to be heated. The bottom of the vertical passage of the lower section is closed to prevent the smoke from escaping, but the same passage of the upper section is open to receive the air from the lower section. These tube-sections of the stove may be made in cast or wrought iron, or other material, as preferred; but for cheapness of construction they will generally be cast.

Having thus described our invention, we claim as new and desire to secure by Letters Patent—

The shell or cylinder of the stove constructed in one or more sections, B, having radial air-inlets D and a vertical outlet, F, connecting with a passage through the top, substantially as specified.

WILLIAM M. MORSE.
MORRIS G. KNOX.
